UNITED STATES PATENT OFFICE.

WILLIAM ANDERSON, OF HULTON, PENNSYLVANIA.

DESIGN FOR A MANTEL.

SPECIFICATION forming part of Design No. 19,873, dated June 3, 1890.

Application filed February 20, 1890. Serial No. 341,217. Term of patent 7 years.

To all whom it may concern:

Be it known that I, WILLIAM ANDERSON, a citizen of the United States, residing at Hulton, in the county of Allegheny and State of Pennsylvania, have invented certain new and useful Improvements in a Design for Mantels B B; and I do hereby declare the following to be a full, clear, and exact description of the invention, such as will enable others skilled in the art to which it pertains to make and use the same, reference being had to the accompanying drawings, which form a part of this specification.

In the accompanying drawings, Figure 1 is a front elevation of a mantel showing my design. Fig. 2 is a sectional elevation of the same, these two views being deemed necessary to illustrate my design.

In the drawings, *a* represents the pilasters, which extend from the hearth to the mantel-board *m*, and are provided at the top with cap-pieces *b*, each of which has formed on its front face rosettes *c* and beveled lower edges *d*. These pilasters *a* are provided with a double series of reeds *e* extending in the direction of their length, and also with beveled

outer edges of the same length as the reeds *e*. A short distance below the lower extremities of the reeds *e*, and transversely across the pilasters *a*, is a deep V-shaped groove *f*. The frieze *g* of this mantel has a series of reeds *h* extending in the direction of its length and a beveled lower edge. Beneath the frieze *g* is a quarter-round molding *i*, and at the top of the same is arranged a backing-strip *k* with a lower molded edge. This strip *k* and the caps *b* are flush, which forms a ground for a suitable molding *l*, arranged beneath the mantel-board *m*. The mantle-board *m* is molded about its upper front edges. The grounds *n* and fire-strips *c* have plain surfaces.

Having thus described my design, I claim—

The design for a mantel, as herein described and shown.

In testimony that I claim the foregoing I hereunto affix my signature this 8th day of February, A. D. 1890.

WILLIAM ANDERSON. [L. s.]
In presence of—

C. C. LEE,
M. E. HARRISON.
